ATTORNEYS

UNITED STATES PATENT OFFICE.

RODNEY H. BRANDON, OF ANDERSON, INDIANA.

DESIGN FOR A BADGE.

42,267.

Specification for Design. Patented Mar. 12, 1912.

Application filed November 28, 1911. Serial No. 662,923. Term of patent 3½ years.

To all whom it may concern:

Be it known that I, RODNEY H. BRANDON, a citizen of the United States, residing at Anderson, in the county of Madison and State of Indiana, have invented a new, original, and ornamental Design for a Badge, of which the following is a specification, reference being had to the accompanying drawing, forming part thereof.

The figure is a face view of a badge or similar article, showing my new design.

I claim:

The ornamental design for a badge as shown.

RODNEY H. BRANDON.

Witnesses:

FLORENCE B. WELLS,
L. D. DINGMAN.
